US0D1040781S

(12) **United States Design Patent** (10) **Patent No.:** **US D1,040,781 S**
(45) **Date of Patent:** ** **Sep. 3, 2024**

(54) **REMOTE CONTROL PAGE TURNER**

(71) Applicant: **Tianjin Changqingshu Trading Co., Ltd.**, Tianjin (CN)

(72) Inventor: **Yilin Xiao**, Linqing (CN)

(73) Assignee: **Tianjin Changqingshu Trading Co., Ltd.**, Tianjin (CN)

(**) Term: **15 Years**

(21) Appl. No.: **29/938,008**

(22) Filed: **Apr. 18, 2024**

(51) **LOC (14) Cl. 14-03**

(52) **U.S. Cl.**

USPC **D14/218**

(57) **CLAIM**

The ornamental design for a remote control page turner, as shown and described.

DESCRIPTION

FIG. 1 is a bottom, front and right side perspective view of a remote control page turner showing my new design; FIG. 2 is a top, front and right side perspective view thereof; FIG. 3 is a top, rear and right side perspective side view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.

The broken lines show the portions of the remote control page turner that form no part of the claimed design.

1 Claim, 9 Drawing Sheets
